UNITED STATES PATENT OFFICE

JAMES A. JOHNSON AND GEORGE A. BENSON, OF VIRGINIA BEACH, VIRGINIA, ASSIGNORS TO DRAFT-RATER CORPORATION, OF NORFOLK, VIRGINIA, A CORPORATION OF VIRGINIA

DRAFT CONTROL FOR STEAM-BOILER FURNACES

Application filed March 3, 1928. Serial No. 258,976.

This invention relates to draft controlling means for steam boiler furnaces or like mechanisms, and the general object of the invention is to provide means for reducing the draft either upon a sudden increase in the draft as, for instance, when fresh coal is thrown upon the fire, or the reducing of the draft when an excess of steam is being generated, or in other words when the pressure of the steam has risen above a predetermined point.

A further object is to provide for this purpose a draft damper or valve operating in connection with a stack, and provide readily adjustable means whereby the damper may be held in a normal position at a predetermined distance from the lower end of the stack, the damper being adjustable to increase or decrease this distance, and further in this connection to provide means tending to resist the initial movement of the damper toward the stack or toward the seat but permitting a sudden closing of the damper.

Still another object is to provide means whereby the damper, as before remarked, will be shifted toward its seat to reduce or check the draft through the stack when steam has been raised beyond a certain pressure, which includes a relief valve, a cylinder into which the relief valve exhausts, the cylinder having a piston operating upon the damper to shift it toward the stack when the piston is subjected to the pressure of the steam, thus rendering the action of the damper automatic where the steam is being produced in excess of requirements.

Other objects will appear in the course of the following description.

Our invention is illustrated in the accompanying drawings, wherein:—

Figure 1 is a front elevation of the smoke box of a steam boiler with the front wall thereof removed, showing our draft regulator applied to the interior thereof;

Figure 2 is a vertical sectional view on the line 2—2 of Figure 1;

Figure 3 is a fragmentary sectional view showing the draft regulator applied to a modified form of flue;

Figure 4 is a fragmentary sectional view

showing another application of the draft regulator.

Referring to these drawings, 10 designates the smoke box of a water heater or boiler and 11 designates the fire tubes extending through the boiler 12 and entering the smoke box, the smoke box being provided with the usual stack 13 extending therefrom. It will be understood that the furnace may be of any suitable or usual type and that the embodiment which we have illustrated is purely illustrative of one application of our invention.

Disposed within the smoke box is a cylinder 14 having therein a float 15. This float carries a stem 16 extending upward through a guide 17 of any suitable character. At its upper end this stem carries upon it the bell-shaped damper 18 which is larger than the opening into the stack through the top of the smoke box. This damper will never, even at its highest point, seat against the lower end of the stack so as to completely cut off the draft but the damper may be shifted into a position of approximate contact with the lower end of the stack or with a seat inside the stack, as desired, and under these circumstances will cut down or reduce the draft materially. The damper is retained in a normal position spaced from the lower end of the stack or from its seat by the weight of the damper, the stem or rod 16 and the weight of the float 15. This float is normally supported by a body of water or other liquid disposed within the cylinder 14 which is maintained at any desired height by means now to be described. From the cylinder 14 there extends a pipe 19 which opens into a cylindrical container 20.

Entering into the container is a discharge pipe 21 which is vertically shiftable through a guide bracket 22 and is held in a shifted position by a set screw 23 or equivalent device. The upper end of this pipe 21 is connected by a flexible pipe 24 to the lower end of a tank 25, this tank 25 being a closed tank and having therein a certain amount of water. It will be obvious now that the level of water within the container and, therefore, the level of water within the cylinder 14 will depend

upon the adjustment of the pipe 21 and that the container 20 will be filled up to a point where the lower end of the pipe 21 is closed or sealed by the water within the container 20 and that then further discharge of water 5 through the pipe 21 is stopped. Thus by raising or lowering the pipe 21, the height of the water within the float chamber 14 may be regulated and this, of course, will regulate the height of the float 15 and the distance of 10 the valve or damper 18 from its seat.

Under these circumstances, if a sudden draft is caused upward through the stack, such a draft, for instance, as is caused by the 15 opening of the furnace door and the throwing of fresh coal in upon the fire which causes what may be termed a smoke explosion, the force of the draft rushing out through the smoke stack will cause the 20 damper to move toward the stack, thus reducing the draft and preventing the escape up the stack of the hot air and other heated products of combustion and the consequent loss of heating power. A mere slow increase of 25 draft, however, will not cause this upward movement of the damper as the damper is held down by the weight of the damper rod and the float.

While the float is supported within the 30 water, the lower portion of the float has no weight but as soon as the float is free from the water it has an additional weight tending to check the upward movement of the damper. As soon as the draft has been 35 reduced below a certain point, of course, the damper will fall to its initial position which is governed by the adjustment of the pipe 21, as heretofore stated.

In order to provide for an automatic movement of the damper toward its closed position when an excess of steam is being generated, we mount upon the damper rod the cross bar 26 or an equivalent element and mount upon the side of the cylinder 14 beneath this cross bar a cylinder 27 within which 40 a piston 28 operates, this piston having a stem extending upward through the top of the cylinder and bearing against the under face of the cross bar 26. The lower end of 45 the cylinder 27 is connected by means of a pipe 29 to the casing 30 of a relief valve of any usual or suitable type, this relief valve being so set by the usual mechanism for 50 this purpose that it will pop off or relieve the pressure when the pressure is about five pounds below the predetermined pressure required to operate the usual pop-off valve. This casing 30 is connected by a pipe 31 to the steam drum of the engine or to any other 55 suitable chamber having therein steam generated by the boiler. It will, therefore, be obvious that if an excess of steam is created and the pressure increases beyond a predetermined point that the relief valve will act, 60 permitting the steam to pass from the pipe

31 into the pipe 29 and thence into the cylinder 27.

This will lift the piston 28, lift the cross bar 26, and raise the damper 18 toward the stack, thus reducing the draft and consequently reducing the steam and its pressure. Thus it will be seen that we have provided an automatic draft regulator and an automatic steam regulator or pressure regulator which will act to impede or reduce draft passing through the stove either upon a sudden increase of draft or upon an increase in the steam pressure beyond a predetermined amount to which the relief valve is set. 70

In Figure 3, we have illustrated a construction operating on exactly the same principle as heretofore described, except in this case the stack 13^a is shown as angular in form with the float chamber 14 disposed below the bend of the stack and in axial alignment with the axis of the stack, and in this case the float chamber is disposed not within a smoke box but below the stack. Otherwise than this it operates in exactly the same manner as the construction first described. 80

In Figure 4, we illustrate another variation of our construction wherein a header 3 is provided into which two stacks 13 open, these stacks leading from separate furnaces and from which a stack 13^b extends. The damper 18 is disposed beneath the lower end of the stack 13^b and the stem of this damper is mounted upon a lever 32, the outer end of which carries the vertical stem or rod 34 which extends downward and connects to the float disposed within the float chamber 14. It will be seen that this is also a mere variation in the arrangement of parts and does not depart from the invention. 90

While we have illustrated certain details of construction and arrangement of parts, it is to be understood that this is purely illustrative of the several embodiments shown and to illustrate the general features of the invention and how it may be applied and that we are not to be limited to these details except as defined in the appended claims. 105

We claim:

1. In a furnace having a smoke box and a smoke flue extending therefrom, a damper mounted within the smoke box and below the lower end of the flue and adapted to move toward or from the flue, the damper being movable toward the flue under the suction created by an increased draft through the flue, a vertically disposed rod upon which the damper is mounted, means acting to limit the downward movement of the rod and damper, said means comprising a float mounted upon the rod, a liquid chamber in which said float is disposed, and manually operable means for increasing or decreasing the amount of liquid in the chamber. 115

2. In a furnace having a smoke flue, a damper movable vertically under the action 120

of an increase of draft through the flue to reduce the effective area of the flue passage, said damper being urged away from this last named position, a liquid chamber, a float therein operatively connected to and movable with the damper, a barometric tank, a liquid container disposed on a level with the liquid chamber and communicatively connected thereto at its lower end, and a pipe entering said container and operatively connected 10 to the tank to take liquid therefrom, the pipe being vertically adjustable to thereby control the level of liquid in the container and in said chamber.

2. In a furnace having a smoke flue, a damper movable under the influence of excessive draft to reduce the effective area of the flue, a liquid chamber, a float therein operatively connected to and movable by and with the damper, the float being normally supported by the liquid and supporting the damper.

4. In a furnace having a smoke flue, a damper movable under the influence of excessive draft to reduce the effective area of the flue, a liquid chamber, a float therein operatively connected to and movable by and with the damper, the float being normally supported by the liquid and supporting the damper, and adjustable means for controlling the height of liquid in the chamber.

5. In a furnace having a smoke flue, a damper movable under the influence of excessive draft to restrict the flue opening, a receptacle containing liquid, a member therein and connections between the member and the damper whereby as the damper moves to restrict the opening of the flue, the member is withdrawn from the liquid and applies its weight as a bias returning the damper to its normal position.

6. In a furnace having a smoke flue, a damper movable under the influence of excessive draft to restrict the flue opening, a receptacle containing liquid, a member therein and connections between the member and the damper whereby as the damper moves to restrict the opening of the flue, the member is withdrawn from the liquid and applies its weight as a bias returning the damper to its normal position, and adjustable means for controlling the liquid level in the receptacle.

7. In a furnace having a smoke flue, a damper movable under the influence of excessive draft to restrict the flue opening, a receptacle containing liquid, a member therein and connections between the member and the damper whereby as the damper moves to restrict the opening of the flue, the member is withdrawn from the liquid and applies its weight as a bias returning the damper to its normal position, a barometric tank, a liquid container disposed on a level with the liquid 65 receptacle and connected therewith, a pipe

entering said container and vertically adjustable with relation thereto, said pipe being connected to the barometric tank to deliver liquid therefrom.

In testimony whereof we hereunto affix our signatures.

JAMES A. JOHNSON.
GEORGE A. BENSON.
